UNITED STATES PATENT OFFICE.

DELBERT J. REYNOLDS, OF MINNEAPOLIS, MINNESOTA. ASSIGNOR TO JAMES W. DE CAMP, OF BLACKWELL, OKLAHOMA.

CASKET-PANEL.

1,343,280.

Specification of Letters Patent. Patented June 15, 1920.

Application filed October 24, 1918. Serial No. 259,576.

To all whom it may concern:

Be it known that I, DELBERT J. REYNOLDS, a citizen of the United States, residing at Minneapolis, in the county of Hennepin and 5 State of Minnesota, have invented certain new and useful Improvements in Casket-Panels, of which the following is a specification.

This invention has as its object the provision 0 of a panel for caskets, and more particularly a panel designed for application to the lid or one or more of the walls of a transparent, translucent, or opaque glass casket.

5 The invention contemplates the provision of means whereby the lid or one or more walls of a glass casket may be furnished with a permanent embellishment initially 10 separate from the casket but readily attachable thereto in a manner to become substantially an integral part thereof so that even to the last moment in the burial period the casket will retain all of its features of embellishment instead of being stripped, as 15 is at present customary, prior to lowering of the casket into the grave, of the flowers, wreaths, symbolic paraphernalia and the like with which it had been previously decorated.

19 The invention further has as its object to so construct the casket and the panel to be applied thereto that the panels may be made in various designs representative, for example, of floral wreaths or sprays, the emblems of fraternal orders, religious emblems and the like, or the panels may be designed to receive religious paraphernalia such for example as scapulars, holy water founts, photographs, written records, obituary notices, printed matter, trinkets, and the like, thus enabling the purchaser of one of the caskets to make a selection from a great variety of designs.

As surface ornamentation in relief may at best only imperfectly imitate the floral design or the like with which the casket is to be embellished, it is the object of the invention to so construct the panel that when in place upon the casket there will be produced an almost undetectable facsimile of the wreath, spray, or other embellishing design, appearing as though laid beneath the glass lid of the casket in a manner to be visible therethrough. In order to produce

this natural effect the present invention contemplates the molding of the design or embellishment in that face of the panel which is to contact the lid of the casket, whether the panel be applied to the outer surface of the lid as in one form of the invention or to the inner surface of the lid as in another form. The panels being of clear glass will, of course, display the design or embellishment in a highly artistic and attractive manner and, as above stated, to affect the sense 65 of vision by an impression of the natural article or design itself laid beneath and within the transparent lid of the casket.

A further object of the invention in constructing the panel as before stated, is to add to the permanency of the design or embellishment beyond that which it would possess if molded in relief upon the outer or exposed surface of the panel, for in the latter instance there would be likelihood of portions of the embellishment being broken off or the paint or enamel scoured or soiled so as to detract from the beauty of the panel.

Another object of the invention is to provide means whereby the panel may be readily applied and permanently secured to the lid of the casket so as to become a permanent and substantially integral part thereof, and without the use of bolts or any other fastening devices requiring the drilling of holes.

In the accompanying drawings:

Figure 1 is a perspective view illustrating the panel embodying the present invention applied to the lid of a glass casket;

Fig. 2 is a vertical transverse sectional view through the panel and casket illustrating the manner in which the panel is arranged when applied to the outer face of the lid;

Fig. 3 is a similar view but illustrating the panel applied to the inner face of the casket lid;

Fig. 4 is a perspective view of the panel looking at the obverse side thereof;

Fig. 5 is a similar view looking at the reverse side thereof;

Fig. 6 is a fragmentary perspective view of a portion of the panel illustrating the manner in which the design or embellishment is to be molded therein;

Fig. 7 is a view similar to Fig. 3 illustrating a modified form of panel.

In the drawings the body of the casket is indicated in general by the numeral 1 and the lid by the numeral 2, the said body and lid being molded from glass and the lid 5 being preferably transversely curved as clearly shown in Figs. 2 and 3 of the drawings. In that form of the invention shown in Fig. 2 of the drawings, the lid is formed in its upper or outer surface with a shallow 10 depression or recess 3 to receive the panel, the said recess having its bottom wall, indicated by the numeral 4, transversely curved to conform to the curvature of the said surface of the lid. The side walls 5 of the depression or recess 3 are substantially perpendicular and therefore occupy substantially parallel planes. In that form of the invention shown in Fig. 3 of the drawings, the under or inner surface of the casket lid 15 2 is formed with a recess or depression 6 corresponding to the recess 3 and having a bottom wall 7 transversely curved to correspond to the curvature of the lid, and perpendicular side walls 8. Of course, in the first described form the panel will be applied to the outer or upper side of the lid, whereas in the second described form the panel will be applied to the under or inner side of the lid. In either event the panel 20 30 will be of clear glass and the said panel is indicated in general in the drawings by the numeral 9. The panel in marginal outline is here illustrated as rectangular although it will be understood that it may be circular, oval, or of any other desired marginal contour. The said panel is transversely curved and therefore its convex and concave faces describe substantially a portion of a cylindrical surface, and, of course, the 35 curvature of the panel corresponds to the transverse curvature of the casket lid 2. When the panel is to be applied to the outer or upper surface of the casket lid its convex face will be smoothly finished, and the 40 design or embellishment, indicated in general by the numeral 10, will be molded in its concave face as clearly shown in Figs. 5 and 6 of the drawings. In producing the design or embellishment, the same is molded 45 or pressed in the said concave face of the panel as indicated by the numeral 11, and the depressed surfaces are then stained, painted, enameled, or otherwise treated to produce the colors of the natural articles 50 represented. Of course, in producing the design in this manner, the same will be visible through the convex face of the panel and the impression received will be that of the natural article represented, laid or arranged 55 beneath the top of the lid. Of course, in some instances, if desired, as for example in religious symbols or the emblems of fraternal orders the design may be represented by frosting the same upon 60 the under surface or concave side of the 65

panel, or by frosting the entire under surface of the panel with the exception of portions which define the design to be represented.

In the form of the invention just described, the panel 9 has its edges beveled at its convex face as indicated by the numeral 12 and consequently when the panel is disposed within the recess 3 in the manner clearly shown in Fig. 2 of the drawings, 70 a groove 13 will be formed between the walls 5 of the recess or depression and the beveled edges 12 of the panel 9. After the panel has been disposed in place as shown in the said figure, a suitable cement, as for 75 example water-glass, indicated by the numeral 14 is poured into the groove 13 and allowed to harden flush with the transversely curved or rounded upper surfaces of the panel and casket lid. As this cement 80 is of itself transparent, its presence will be barely noticeable if it is carefully placed, and consequently the lines of division between the edges of the panel and the casket lid will be substantially indistinguishable, 85 although for the purpose of illustration these lines have been greatly exaggerated in Fig. 1 of the drawings in order that the outline of the panel may be defined in the 90 said figure. 95

In that form of the invention shown in Fig. 3 of the drawings, the design or embellishment is molded in the convex surface of the panel and the under or concave surface of the panel is left smooth. In this 10 case, however, the design or embellishment will be visible through the transparent lid 2. Also in this form of panel the edges thereof are beveled at the concave side so as to provide the cement receiving groove 10 as shown in the said Fig. 3.

In both forms of the invention it will be evident that the design or embellishment molded in or carried by the panel will be visible through a transparent medium, in 11 one instance the panel itself and the other instance the lid of the casket. In any event the impression received by the eye will be substantially the same and, as before pointed out, will be that of the natural flowers, 11 or other objects represented in the design, arranged in an artistic and attractive manner within the lid and beneath the top thereof.

As before stated, the panel when united 12 by the cement to the casket lid, becomes substantially an integral part of the lid, restoring to the lid the thickness initially lost by the formation of the recess in the lid, and also compensating for any weakening 13 effect upon the lid due to the formation of this recess.

The panel shown in Fig. 7 of the drawings is provided in its upper face with a recess or pocket 15 into which may be placed 1

a photograph, papers, religious paraphernalia, or in fact any article or articles 16 which it is desired to inter with the body.

While the panel is illustrated in the drawings as applied to the lid of the casket, it will be readily understood that similar panels may be applied to any one or more walls of the casket. It will also be understood that the panels may be applied to glass 10 caskets whether transparent, translucent, or opaque.

While the panels to be employed have been heretofore described as possessing certain characteristics, it will be understood 15 that these panels may if desired be made of cut glass in various artistic designs and may be applied to various parts of the casket so as to give to the casket the appearance of being in its entirety of cut glass. In 20 this manner a highly ornamental casket may be produced at a relatively low cost.

Having thus described the invention, what is claimed as new is:

1. The combination with a transparent

casket wall having a recess therein, of a 25 transparent embellishing panel disposed within the recess and bearing a design or embellishment visible because of said transparency.

2. The combination with a casket wall 30 having a recess therein, of a transparent embellishing panel disposed within the recess and bearing a design or embellishment visible because of said transparency, the edges of the panel being beveled where to 35 provide between them and the walls of the recess, a groove, and cement occupying said groove.

3. The combination with a casket wall having a transparent portion formed with 40 a recess, of a transparent panel of the same material as the casket wall seated within the recess and having a face which confronts the inner wall of the recess provided with a representation of an object in appropriate 45 colors produced in the said face in relief.

In testimony whereof I affix my signature.
DELBERT J. REYNOLDS. [L.S.]
